UNITED STATES PATENT OFFICE.

CHARLES B. HARLAND, OF SAN FRANCISCO, CALIFORNIA.

DESIGN FOR A STATUETTE.

Application filed September 22, 1924. Serial No. 10,868. Term of patent 3½ years.

To all whom it may concern:

Be it known that I, CHARLES B. HARLAND, a citizen of the United States of America, and a resident of the city and county of San Francisco, State of California, have invented a new, original, and ornamental Design for Statuettes, of which the following is a specification, reference being had to the accompanying drawing, forming part thereof.

I claim:

The ornamental design for statuette substantially as shown.

CHARLES B. HARLAND.
